UNITED STATES PATENT OFFICE.

ADOLPH C. MENNINGEN, OF WEST ALLIS, WISCONSIN, ASSIGNOR TO KOEHRING COMPANY, OF MILWAUKEE, WISCONSIN, A CORPORATION.

MULTIPLANE SHOE.

Application filed February 4, 1924. Serial No. 690,567.

This invention embodies a novel construction of traction shoe. Shoes of this class are used primarily today as units of an endless traction or tread device upon which heavy machines are mounted to travel.

The manufacture of traction shoes, such as above referred to, involves some peculiar problems. These shoes, when built in accordance with the present invention, comprise off-standing pivot lugs at opposite edges of each shoe. The pivot lugs receive pintles or pivots or pivot rods, by which a plurality of shoes are connected together to form an endless chain. It is fundamentally necessary in the formation of a shoe having the pivot lugs at its opposite ends, that the axes of said lugs be an accurate predeterminate distance from one another, as respects the lugs at one edge of the shoe 20 in their relation to the lugs at the other edge of the shoe when the shoe is of an integral construction as used for the present invention.

If the distance between the centers of the pivot lugs of one edge of the shoe, and the centers of those at the opposite edge, varies to even a slight extent transversely of the shoe, a condition of non-parallelism of the pivots or pintle rods will be created. The foregoing results in the production of an endless tread of inaccurate construction, for obviously if a lug or lugs at one edge of a shoe are a greater distance from the corresponding lugs at the opposite edge of the shoe near such end, this inaccuracy of formation is many times multiplied when it is borne in mind that thirty or forty of these shoes are frequently assembled to make a single endless tread or traction member. The result would be a distorted traction member or tread construction, unless by careful matching or arranging of the treads the shoes can be assembled to compensate for the possible non-parallelism of the axes of the pivot lugs as above described. In any event, however, an endless tread of accurate length is difficult of production when the pivot lugs are not exactly equally spaced apart respecting their axial centers, in a manner which will be self-evident from the foregoing explanation.

It is one of the objects of the present invention to obtain a new construction of wholly integral traction shoe, and subsidiary to said object is involved the employment

of a construction of such shoe whereby it may be cast readily and yet with complete accuracy as regards the features hereinbefore discussed. Additionally, it is contemplated that the shoe shall be one of substantial construction possessing great rigidity and strength to enable it to stand up under the tremendous strain and enormous wear and tear service which a shoe of this character must sustain when it forms a part of the traction support of large machines, such as concrete pavers, cranes, and the like.

A full understanding of the invention will be had upon reference to the accompanying drawings, in which:

Figs. 1, 2 and 3 are, respectively, top plan, front, and longitudinal sectional views of a traction shoe made in accordance with the invention.

Figs. 4, 5 and 6 are views corresponding with Figs. 1, 2 and 3, but illustrating a modified construction of shoe.

In the following specification and the accompanying drawings, similar reference characters designate similar parts throughout.

The drawings are referred to at this time and it will be apparent therefrom that the shoe of the invention comprises a base or tread 1, the same of a greater width than length, considering the device in the sense of the width of the ultimate endless traction member of which it will form a part. The base or tread 1 is relatively flat over its main body portion on its bottom, and it has its side extremities, which may be termed its ends, slightly curved upwards as shown at 1^a. The tread 1 is formed on its top with the front and rear flanges 2, which carry the oppositely extending series of pivot lugs 3 and 4. The series of lugs 3 are staggered in their relation to the series of lugs 4, as respects the points at which they project from the flanges 2 of the shoe. The several lugs 3 and 4 are apertured so that their openings 5 accurately align with one another to receive the pivots or pintles by which one shoe is connected to adjacent shoes.

On its top, the tread 1 is provided with longitudinal ribs 6, disposed in a slightly diagonal direction as regards the longitudinal axis of the shoe, and in addition to these ribs there are provided other accurately longitudinal ribs or webs 7, the several ribs 6 and 7 joining with the front and rear flanges 110

2 and being of substantially the same height, in respect to their degree of projection from the base or tread 1, as are the flanges 2. There is also provided a transverse rib or web 8, extending centrally across the body of the shoe, of the same height as the ribs 6 and 7, and joining said ribs at the central points of the latter in the integral formation of the device.

10 It is common to employ a driving lug for traction shoes of the type of the invention and in the present instance said lug is designated 9 and projects from the top of the shoe as an integral extension of a flat reinforcing web 10, which extends over the top of the shoe at its central portion, being united with the ribs 7 and the central portion of the rib 8. The flanges 2, ribs 6, 7 and 8 form a skeleton rib construction, virtually 15 speaking, at the top of the shoe, designed to brace the lugs 3 and 4 against certain strains, to brace the whole body of the shoe at its tread both transversely and longitudinally, and to support and brace the driving lug 9.

20 The several ribs 6, 7 and 8 and flanges 2 establish open and closed cavities above the tread 1 of the shoe; the closed cavities being beneath the driving lug 9, which it will be noticed is reinforced in its connection 25 with the shoe not only by its integral formation with the covering web 10 but through the strengthening connection it has with the middle of the rib 8 and the middle portion of the flanges 2.

30 The matter of rendering the axes of the lugs 3 and 4 accurately parallel with one another involves a peculiar casting operation. It will be noticed that the cavities *a*, *b*, *c* and *d* formed between certain of the ribs described have openings 11 leading therefrom to the apertures or openings 5 of certain of the pivot lugs 3 and 4. The cavities *a* and *c* have openings 11 which communicate with apertures of two lugs 3 and 45 apertures of two lugs 4, respectively, whereas, the openings 11 leading from the cavities *b* and *d* communicate with only one lug 4 and one lug 5, respectively.

50 The driving lug 9 is hollow in its cast formation, and the cavities *e* and *f* beneath driving lug 9, at opposite sides of the rib 8, have openings 12 which establish communication between them and the openings 5 of one of the lugs 3, for the cavity *f*, and 55 one of the lugs 4, for the cavity *e*.

By reason of the formation and provision 60 of the openings 11, it is possible to tie cores used one for each series of the lugs 3 and 4, to core members by which the cavities in the body portion of the shoe are formed. The ties, for instance, may pass through the openings 11 primarily, and in the casting of the shoe, the core members which form the openings 5 of the lugs 3 and 4 will be maintained 65 in accurate parallelism to insure the result of

construction of a shoe in accordance with the requirements that have been previously elucidated. There are provided large openings 13 in the ribs 7, establishing communication between the cavities *e* and *f* and the other cavities *a*, *b*, *c* and *d*. These openings are adapted to permit of the removal of the molding sand after the casting operation is completed, and the openings 12 assist to the above end.

70 In addition to the several cavities which have been specifically mentioned above, as provided between the ribs and flanges at the top of the shoe, there are small open cavities *g* at the ends of the shoe, largely above the curved portions of the tread 1.

75 Reference is now made to Figs. 4 to 6, inclusive, illustrating a modified construction of the invention, and in these figures the parts which correspond with like parts of Figs. 1 to 3, inclusive, are designated by the same numbers with prime notations annexed thereto. The construction of these Figures 4 to 6, inclusive, has certain advantages from 80 a manufacturing viewpoint and affords additional reinforcing facilities as regards the strength of the shoe built in accordance therewith.

85 Without describing the features which are of the same construction as previously set forth, it is noted that the cavities *a'* and *b'* are covered by an extension of the covering web 10, which extension projects in opposite directions as far as the ribs 6'. Additionally, these cavities *a* and *b* have openings 14 which lead therefrom through the flanges 2' to the spaces between certain of the lugs 3' and 4'. In like manner, other openings 14 extend from cavities *c'* and *d'* to spaces between certain of said lugs 3' and 4'. 100 By this formation the openings 11 and 12 of the construction of Figs. 1 to 3, inclusive, are dispensed with and the connections of the lugs 3' and 4' with the body of the shoe are in no way weakened.

105 One of the webs 7' at the left end thereof is foreshortened and the other web 7' at the right end thereof is foreshortened as shown at 15, so that the molding stand in the cavities *e'* and *f'* may pass therefrom through 115 the openings 14. I still use the openings 18', however, in the web 7', like those previously described. Otherwise, the construction is substantially like that previously set forth.

110 Having thus described my invention, what I claim as new and desire to secure by Letters Patent, is:

1. In the art of forming hollow cast traction shoes having opposing pintle receiving openings, forming a sand mold for the body of such shoe and a core for the body provided with integral parallel cores for the production of said openings, and casting a shoe in the mold and about said cores while maintaining the parallelism of the cores. 120

2. A hollow cast metal traction link for endless chain traction belts comprising a hollow body provided on each of two opposite edges with a series of lugs having aligned cored pintle receiving openings, the openings of one series being parallel with those of the other and each opening communicating with the hollow interior of the body by a cored passage through which the cores of the opposite pintle receiving openings are connected to the core of the body portion and thereby held in parallelism during the casting operation. 10

In testimony whereof I affix my signature.

ADOLPH C. MENNINGEN.
